No. 793,955.

PATENTED JULY 4, 1905.

J. W. PYNCH.

LEGGING.

APPLICATION FILED JAN. 28, 1905.

UNITED STATES PATENT OFFICE.

JAMES WILLIAM PYNCH, OF RIPON, WISCONSIN.

LEGGING.

SPECIFICATION forming part of Letters Patent No. 793,955, dated July 4, 1905.

Application filed January 28, 1905. Serial No. 243,029.

To all whom it may concern:

Be it known that I, JAMES WILLIAM PYNCH, a citizen of the United States, and a resident of Ripon, in the county of Fond du Lac and 5 State of Wisconsin, have invented a new and useful Improvement in Leggings, of which the following is a full, clear, and exact description.

My invention relates to an improvement in 10 laced leggings; and the purpose of the invention is to so construct a legging that it will lace at the front and so that the front will be open for the introduction of the foot only a portion of the length of the legging, the lower part of 15 the front being permanently closed by a folding tongue.

A further purpose of the invention is to 20 provide means of lacing which can be more quickly and conveniently operated than lac- 25 ings of the usual type and to so locate and hold the lace at the bottom of the legging that it will not drop under the foot while the legging is being placed upon the person.

The invention consists in the novel construc- 25 30 tion and combination of the several parts, as will be hereinafter fully set forth, and pointed out in the claims.

Reference is to be had to the accompanying 30 drawings, forming a part of this specification, 35 in which similar characters of reference indicate corresponding parts in all the figures.

Figure 1 is a perspective view of a legging represented as laced upon the leg of a wearer. Fig. 2 is a perspective view of the legging 35 unlaced and open; and Fig. 3 is a horizontal section taken, practically, on the line 3-3 of Fig. 1.

The legging A is open at the front, providing 40 opposing side edges 10 and 11, reinforced at the inner face of the legging by a facing 12 of any stout and pliable material. The space between the two side edges 10 and 11 is open only from a point below the longitudinal center of the legging to the top edge, the 45 lower portion of such space being permanently closed by a tongue 13, which extends to the bottom edge of the legging, as is shown in Fig. 2. The side edge of the tongue 13 is secured to the inner wall of the legging adjacent 50 to its corresponding edges 10 and 11, and the

edges of the tongue are preferably introduced between the side wall of the legging and the facings 12. The tongue 13 is made of any suitable flexible material and is of sufficient width to permit the front of the legging to be 55 opened sufficiently to readily admit the passage of the foot. When the legging is closed for lacing, the tongue folds upon the inner face of the legging and completely covers the space between the edges 10 and 11 at the foot and 60 ankle, and at that time the space between the remaining length of the said side edges 10 and 11 is closed by a flap 14, secured to the edge 10, which flap is sufficiently long to extend over the upper portion of the tongue. 65

Hook-buttons 15 are secured to the exterior of the legging adjacent to the edge 11, and eyelets 16 are produced in the opposite side surface of the legging adjacent to that portion of the edge 10 at the tongue 13, as is 70 shown in Fig. 1, and above the series of eyelets 16 on the same side of the legging a series of hook-buttons 16^a is secured. Two eyelets 16 are employed for each of the two lowermost buttons 15, and the buttons 16^a are 75 arranged alternately with the buttons 15, as is shown in Fig. 1. In one lower corner of the legging an eyelet 17 is made, and a corresponding eyelet 18 is produced at the other lower corner, while at the central lower portion of the tongue 13 one or more eyelets 19 are located.

The lace B is provided with a knot 20 at one end and is passed from the inside out through the eyelet 17, then across the outside of the 85 tongue 13 and through the eyelet or eyelets 19 in the tongue. Thence the lace is passed from the outside through the eyelet 18 and is then laced through the eyelets 16, as is shown in Fig. 2, in such manner as to form 90 two outer loops 21, as is illustrated in Fig. 1.

By referring to Fig. 2 it will be observed that when the legging is opened the lower part of the lace is supported by the eyelet or eyelets 19 and the tongue in such manner that when the legging is being placed on the lower portion of the leg the lower part of the lace cannot loop under the foot. When the legging is on the limb, the flap 14 is turned in, and the two edges are brought conveniently 100

2

together, thus folding the tongue 13. Then the loops 21 are drawn upon, tightly closing the edges of the legging at the bottom, and the loops are passed over the buttons 15 opposite them. Finally the entire lace is placed under tension and carried first over a button 15 and then over a button 16^a until the top button is reached, whereupon the upper end of the lace is secured in any desired manner 10 by means of a clamp 22, for example, secured to the legging.

I desire it to be understood that the above-described manner of lacing is applicable to all kinds of laced leggins, boots, shoes, and 15 rubbers.

Having thus described my invention, I claim as new and desire to secure by Letters Patent—

1. A laced legging provided with a folding support for a lace located between the side 20 edges of the legging at its bottom portion, the said support being provided with openings therein through which the lace is adapted to slide.

2. A laced legging adapted to open at the 25 front, a flexible tongue secured at its side edges to the inner faces of the body of the legging, closing its front opening at the bottom portion thereof, said tongue having an eyelet in its transverse central portion, the body of

the legging being provided with eyelets at its 30 lower front corners, as specified.

3. The combination with the body of a legging or like article of apparel, open at the front and having buttons adjacent to one side edge, and eyelets and buttons adjacent to the opposite side edge, the eyelets being at the lower portion of said side edge, the body of the legging being also provided with an aperture at each lower corner, of a flap secured to the upper portion of one side edge of the body, 40 a folding tongue secured to the body at its lower portion, extending from one side edge to the other, which tongue is provided with an eyelet at its lower central portion, and a lace which is passed through the corner eyelets, through the eyelet in the tongue and across the outer face of the tongue, the said lace being also passed through the eyelets at the side edge of the front opening, being 45 adapted likewise to engage with the buttons 50 adjacent to the front opening, as described.

In testimony whereof I have signed my name to this specification in the presence of two subscribing witnesses.

JAMES WILLIAM PYNCH.
